THE NORRIS PETERS CO., PHOTO-LITHO., WASHINGTON, D. C.

UNITED STATES PATENT OFFICE.

MARTHA EPPLER, OF NEW YORK, N. Y.

BATH-TUB ATTACHMENT.

1,301,114.

Specification of Letters Patent. Patented Apr. 22, 1919.

Application filed December 11, 1917. Serial No. 206,704.

To all whom it may concern:

Be it known that I, MARTHA EPPLER, a citizen of the United States, and resident of New York city, in the county of Bronx and 5 State of New York, have invented certain new and useful Improvements in Bath-Tub Attachments, of which the following is a specification.

My invention relates to a body supporting bath tub attachment for supporting a person in reclining position over the tub when giving a vaginal douche or an enema.

In operations of this character it is preferable that the patient be lying in a reclining, backwardly tilted or dorsal position with a firm support for the buttock, shoulder and head. As persons have different length bodies, and as it is desirable that not only the buttock but also the patient's feet be firmly positioned, it is obviously necessary that the length of the supporting back be adjustable to fit different size patients.

Accordingly, one of the objects of the 25 invention is to provide a simple form of device of the class described, which can be readily positioned on the bath-tub, easily adjusted to suit the requirement of the particular patient being treated, and, which 30 will insure a steady, rigid support for the patient's body and at the same time eliminate any feeling of unsteadiness or unsecurity of support on the part of the reclining patient.

Such devices are of necessity somewhat 35 cumbersome and take up space in the bath room or storage compartment when not in use.

Accordingly another object of the 40 invention is to provide a device of the class described which can be readily separated into a conventional form of bath seat of the hanging type now in general use, and a back element which can be coördinated with the 45 seat whenever it is desired to support the patient in reclining position.

Various other objects and advantages of the invention will be in part obvious from an inspection of the accompanying drawings 50 and in part will be more fully set forth in the following particular description of one form of mechanism embodying my invention, and the invention also consists in certain new and novel features of construction and combination of parts hereinafter 55 set forth and claimed.

Referring to the accompanying drawings:

Figure 1 is a perspective view showing a bath tub with a preferred embodiment of my 60 invention installed thereon;

Figs. 2 and 3 are respectively perspective views of the seat and back element of the attachment shown in Fig. 1;

Fig. 4 is a vertical sectional view taken 65 longitudinally of the device shown in Fig. 1;

Fig. 5 is an upper end view of the back element showing in full lines the supporting legs in operative position and showing in 70 dotted lines the legs in folded position suited for storing;

Fig. 6 is a perspective view of one of the pivoted legs, and Fig. 7 is a view similar to Fig. 4 showing a modified form of leg sup- 75 port for the back.

In the accompanying drawings there is shown a conventional form of bath tub 10 provided with oppositely disposed outlining side rims 11, and a connecting curved 80 rear rim 12, all as is usual in well known devices of this type.

A seat element 13 of conventional form is hung by means of curved wire hook hangers 14 engaging the side rims with the seat 85 board 15 suspended therebetween as is usual with a well known form of bath seat. In this case, however, it is preferable, but not necessary that the seat fit between the sides of the tub to prevent lateral play and that 90 the hangers 14 or at least the forward part thereof be so positioned that it can be used as a support for the heel of the patient when in dorsal position on the device. The rear edge of the seat board is provided with a 95 depending hanger plate 16. The central portion of this plate is recessed to provide an opening 17 adapted to accommodate the adjacent end of the back element 18 herein-after more fully described. The lower edge 100 19 of this opening is beveled to provide a secure engagement with the back element.

It is understood that this seat element can be used as a bath seat and that the depending plate 16 in no way interferes with the 105 use of, or detracts from the appearance of the similar device now in general use.

The back element 18 comprises a body supporting member the lower end 20 of which is adapted to be inserted into the 110 opening 17 in the depending plate 16 and to rest on the edge 19. The body support-

ing part is formed of a plurality of spaced apart and longitudinally extending slats 21. This spacing of the slats provides openings therebetween which facilitate the draining 5 of the back element. The slats are converging to provide a wide support at one end adjacent the patient's shoulders and to permit the use of a small opening 17. The slats are connected by means of two braces 10 22 and 23. The brace 22 is a narrow projecting strip positioned to fit beneath the small of the patient's back, thus assisting to prevent sliding. The brace 23 is a broad flat plate designed to constitute a shoulder 15 or head rest for the patient.

In order to adjust the extent of the portion of the back element which projects rearwardly of the seat element and at the same time to hold the back in position on the seat 20 element, there is provided a plurality of notches 24 spaced longitudinally of the back element and adapted to engage in the edge 19 of the plate.

The upper or outer end of the back is provided with a pair of legs 25 depending from 25 the portion thereof adjacent the shoulder rest 23. The legs are of spring metal and include a curved rim engaging saddle 26 having a curvature to conform to the configuration of the back rim 12 of the tub on opposite sides of its longitudinally medial line. This disposition of the legs places the back in set position on the tub and holds the back to the seat in such a manner as to 30 prevent lateral movement of the back relative to the seat.

In operation and assuming that the seat is in its usual position bridged across the tub and between the sides thereof, it is noted 40 that the seat may be moved toward or away from the rear of the tub into such a position as to give the requisite length of back support when assembled. The back element is then inserted into position in the opening 45 17 with the edge of the plate engaging the proper line of notches so as to bring the legs into position firmly engaging the back rim of the tub. If necessary, the seat is shifted until this secure seating is attained.

50 By means of a device of this character it will be noted that the long engagement of the seat hangers co-act with the spaced apart legs of the back so as to form a widely spreading and braced construction which 55 will hold firmly in place and will not accidentally slip when the patient moves thereon or demounts from the construction. As the hangers 14 are spaced from the side of the tub, they act as guards to prevent the 60 patient's clothing coming in contact with the inner side of the tub. In this way the

douche can be administered without the necessity of the patient undressing. The seat can be tilted forwardly or provided with a forwardly inclined draining surface to discharge the douche water off the seat without wetting the patient's clothes. When finished the back can readily be detached from the seat and the simple construction permits of a ready washing and cleaning of the device before the back is stored away.

While I have shown and described, and have pointed out in the annexed claims, certain novel features of my invention, when considered in connection with a bath tub, it 75 will be understood that it may be used in connection with any proper support such as a couple of chairs and that various omissions, substitutions and changes in the form and details of the device illustrated and in 80 its operation may be made by those skilled in the art without departing from the spirit of the invention.

Having thus described my invention, I 85 claim:

1. In a device of the class described, the combination of a relatively long back element designed to extend longitudinally of a bath tub and spaced from the sides thereof, said back element provided with a supporting member adjacent one end for spacing said end above the rear rim of the tub, a seat element provided with means for suspending the same below the upper edge of the tub, said seat element provided with a hanger plate depending therefrom and recessed to provide a back receiving opening, the end of the back opposite the end having the supporting member adapted to be inserted variable distances into said opening and supported in its adjusted positions by said plate, said seat being adjustable on the tub thereby to vary the angle of inclination of the back.

2. In a device of the class described, a back element comprising a plurality of 105 spaced apart slats and means for fastening the slats together to form an open back adapted to permit fluids to flow therethrough, one end of said back constituting a shoulder rest, the shoulder rest end of the 110 back provided with means for holding the same in place above the rear rim of a bath tub and the opposite end of the back provided with means for pivotally and adjustably supporting the same from a separate 115 supporting member positioned below the rim of the tub whereby the back is inclined.

Signed at New York city, in the county of New York and State of New York this 6th day of December, A. D. 1917.

MARTHA EPPLER.
